ARMLESS CHAIR

Robert A. Gera, Elmhurst, Ill., assignor to International Furniture, Division of Schnadig Corp., Chicago, Ill., a corporation of Delaware

Application May 14, 1956, Serial No. 41,487

Term of patent 3½ years

(Cl. D15—1)

Figure 1 is a perspective view of the armless chair; Figure 2 is a top plan view of the chair; Figure 3 is a front view in elevation; Figure 4 is a rear view of the chair taken in elevation; and Figure 5 is an end view taken in elevation.

I claim:

The ornamental design for an armless chair, substantially as shown.
